Attorneys

tween the two strands (10') of the overlapping unit.

Having thus disclosed my invention, what I claim as new and desire to secure by Letters Patent of the United States is:

1. Woven wire fencing embodying a plurality of wire strands extending transversely of the fencing in uniformly spaced zig-zag paths with each strand extending around and interlocked with the two adjacent strands at the adjacent apices of their paths, a U-shaped wire welded in end to end relation with each two converging strand ends located on opposite sides of and immediately adjacent to each interlocked pair of strands having diverging ends, each U-shaped wire overlapping and underlapping adjacent U-shaped wires.

2. Woven wire fencing embodying a plurality of wire units extending in overlapped relation transversely of the fencing, each unit embodying two spaced wire strands extending in spaced zig-zag

paths transversely across and connected at the margins of the fencing, the said two strands of each unit respectively overlapping two relatively adjacent units and the two adjacent strands of said two adjacent units extending around and interlocking with each other at the adjacent apices of their zig-zag paths.

FRANK J. MAFERA.
